TOOL CARRIER

Isidore C. Myers, Akron, Ohio, assignor to Akro-Mils,
Inc., Akron, Ohio, a corporation of Ohio

Filed Feb. 8, 1968, Ser. No. 10,509

Term of patent 14 years

(Cl. D87—1)

FIG. 1

FIG. 2

FIG. 3

FIG. 4

FIGURE 1 is a front perspective view of a tool carrier showing my new design.

FIGURE 2 is a top plan view thereof on an enlarged scale.

FIGURE 3 is a rear elevation thereof.

FIGURE 4 is an end elevation thereof opposite to that seen in FIGURE 1.

I claim:

The ornamental design for a tool carrier, as shown.
